AUXILIARY VALVE GEAR MECHANISM

Alfred O. Judson, Swanton, Ohio, assignor to The
Pilliod Company, Swanton, Ohio, a corporation
of Ohio

Application December 10, 1934, Serial No. 756,721

4 Claims. (Cl. 121—163)

This invention relates to reciprocable piston engines, but more particularly to steam or expansive fluid engines of the reversible type, and an object is to produce a new and improved auxiliary valve gear mechanism for an invention of this type having the novel features of construction, arrangement and operation hereinafter described.

Further objects and advantages of the invention are hereinafter set forth, and for purposes of illustration, but not of limitation, an embodiment of the invention is shown in the accompanying drawings, in which:

Figure 1 is a side elevation partly in vertical section of a valve gear arrangement, valve chest and associated parts, showing the valve gear in neutral position while the piston is at midstroke;

Figure 2 is a top plan view of the auxiliary valve gear mechanism;

Figure 3 is a vertical sectional elevation of the auxiliary valve gear mechanism taken substantially on the line 3—3 of Figure 4;

Figure 4 is a vertical sectional elevation taken substantially on the line 4—4 of Figure 3;

Figures 5, 6, 7 and 8 are diagrammatic views showing the position of the parts at the points of lead, cut-off, release and compression, with the valve gear adjusted to approximately 25% forward motion cut-off, and Figure 9 is a diagrammatic view similar to Figure 5 showing an inoperative structure having a straight combination lever.

The illustrated embodiment of the invention comprises a valve gear mechanism for imparting reciprocatory movements to the steam admission and exhaust valve, the novel features being illustrated but the remaining parts being omitted, since such parts are well known to those skilled in this art and detailed description and illustration are not considered necessary to an intelligent understanding of this invention. It will be readily recognized by those skilled in this art that the arrangement herein shown and described may be used in conjunction with any well known valve gear mechanism, a portion of the well known Baker gear being illustrated, viz., the bell crank 10 which derives its oscillatory movement through a system of links and levers, eccentric pin 11 on the driven wheel 12 of the engine or locomotive.

To the lower end of the vertical arm of the bell crank 10 is pivoted a valve rod 13, which inclines forwardly and upwardly, the forward end being pivotally mounted on a pin 14 carried by the bifurcated upper end 15 of a vertically

disposed combination lever 16, the bifurcated upper end portion 15 of the combination lever providing arms 15^a and 15^b and the outer end of the valve rod 13 being disposed between these arms. Pivotedly connected to the lower end of the combination lever 16 is a union link 17, which is connected in the usual manner to the main crosshead 18 of the engine, which in turn is connected by the usual connecting rod 19 to the driven wheel 12 of the engine. 10

The combination lever 16 is suspended or supported from a valve stem crosshead guide 20 by a pair of radius bars 21 disposed on opposite sides of the combination lever. The upper ends of the radius bars 21 are bifurcated and are pivotally connected to brackets 22 depending from the crosshead guide 20, and at their lower ends the radius bars are connected to a lower end portion of the combination lever by a pin 23. The pin 23 is disposed a relatively short distance upwardly 20 from the lower end of the combination lever.

Reciprocable horizontally in the crosshead guide 20 is a valve stem crosshead 24, the forward end of which is connected by a stem 25 to a spool valve 26 of the usual type, which reciprocates in bushings 27 disposed within a valve chest 28 having cylindrical ports 29 arranged in the usual manner at opposite ends of the chest. Steam is admitted in the usual manner through a central steam admission passage 30 and ports 31 in the bushings 27 to enable admission of live steam to and exhaust of spent steam from the cylinder 32 through passages 33 at opposite ends of the cylinder. A piston 34 is reciprocable within the cylinder 32 and is connected to the main 35 engine crosshead 18 by a piston rod 35.

The arms 15^a and 15^b of the combination lever 16 are formed with rearward extensions 36, and mounted in the rearward extensions 36 is a pin 37 to which are connected arms 38 of a yoke 39, 40 the opposite end of which is pivotally mounted on a pin 40 secured to the valve stem crosshead 24. It will be noted that the arms 38 of the yoke 39 are disposed on the outer sides of the arms 15^a and 15^b of the combination lever 16. 45

It will be understood that the usual valve gear arrangement, of which the bell crank 10 forms a part, imparts the port opening travel to the valve 26 through the above described connections, and the operation of this gear is controlled in the 50 usual manner from a remote point, such as the locomotive cab, for increasing or diminishing the percentage of the cut-off and the direction of movement of the locomotive or engine. Detail description of this mechanism and the opera- 55

tion thereof is not considered necessary here for a proper understanding of this invention. The lap and lead movements for the valves are obtained from the movements imparted to the 5 combination lever 16 from the main crosshead 18. These mechanisms operate conjointly in such manner that movement of the valve 26 is accelerated at the desired points in its travel as well as retarded at the desired points in order 10 to effect acceleration and dwell in the proper position. Retardation of the valve movement is desired as soon as a volume of steam is supplied to the main cylinder 32 sufficient to drive the piston by its expansive properties in one direction 15 so that the valve closes the respective port openings and fully opens the exhaust, thereby making most efficient use of the expansive properties of the steam.

The acceleration of movement and dwell in the 20 travel of the valve 26 are due to the manner in which the combination lever 16 is constructed and connected to the valve stem 25 and valve rod 13. This auxiliary gear operates on the principle of a variable lap instead of a constant lap, 25 as generally used heretofore, and that the distance between the pin 40 and pin 14 varies at different points in the piston stroke. On each dead center these parts are at their maximum distance apart, but at mid-stroke they are at 30 their minimum distance apart. This variation in the relative positions of the pins 40 and 14 is caused by the swinging movement of the radius bars 21 which operate gradually to raise the combination lever 16 as they approach from 35 midposition to each end of their stroke and gradually to lower the combination lever as they swing from their end or extreme positions to midposition.

Such variation in the relative position of the 40 pins 40 and 14 causes the valve 26 to accelerate on each end of the valve stroke and to retard in the middle of the stroke, thereby producing larger steam and exhaust openings when the engine is operating at relatively short cut-offs. 45 Retardation of the central portion of the valve travel operates to lengthen the expansion period between the events of cut-off and release, and also to cause the event of compression to come later in the stroke, since it enables the piston 34 50 to travel a greater distance before the valve 26 operates to cover or uncover the cylinder ports 31.

It is to be understood that movement of the valve 26 is accelerated due to the swinging movement of the radius bars 21, causing the combination 55 lever to move upwardly or downwardly depending upon the direction of swinging movement, thereby decreasing the distance between the pins 40 and 14, which operates to decrease the effective movement of the combination lever 60 16 with respect to the valve and allow the valve gear proper through the valve rod 13 to accomplish the valve movement. Such acceleration takes place during movement of the valve 26 from lead position to full steam port opening before reaching the cut-off position, and also during 65 the movement of the valve from point of release to end of stroke. Movement of the valve 26 from cut-off position to release position or in the intermediate portion of its travel because 70 the valve rod 13 and combination lever 16 are being moved in the same direction but the effective movement of the combination lever is decreased for the reasons above explained, inasmuch as the distance between the pins 40 and 75 14 are gradually decreased.

It will be readily understood by those skilled in this art that the port opening movements are imparted to the main valve 26 by the valve rod 13 and main gear mechanism deriving motion from the driven wheel 12. The lap and lead movements for the valve, however, are effected through the link and lever connections with the main engine crosshead 18 and supplement those movements imparted by the valve rod. The port opening movements may be varied according to 10 the desired percentage of cut-off, but the lap and lead movements are non-adjustable or operate in substantially the same manner regardless of the percentage of cut-off imposed on the valve rod. 15

The operation of the above described mechanism will be apparent from an examination of Figures 5 to 8, which show the position of the parts at the points of lead, cut-off, release and compression. In Figure 5 the parts are at leading 20 position, steam being admitted to the forward end portion of the cylinder to drive the piston 34 to the left, the port 31 at the rear end of the cylinder being open to exhaust. It will be understood that the valve 26 travels a short distance forwardly in the direction of the arrow as the piston 34 starts its movement in the opposite direction. In Figure 6 the cut-off position is shown in which the valve 26 has permitted the desired 25 volume of steam to pass to the cylinder through the forward cylinder port 31 and has moved to close such port. The movement of the valve 26 from lead position to full steam port opening before reaching cut-off, is accelerated due to the swinging movement of the radius bars 21, causing 30 the combination lever 16 to move downwardly, thereby decreasing the distance between the pins 14 and 40, which operate to decrease the effective movement of the combination lever with respect to the valve gear and allows the 35 valve gear proper through the valve rod 13 to accomplish the valve movement. The movement of the valve 26 from full steam port opening to the point of cut-off is retarded because the valve rod 13 and combination lever are moving in the 40 same direction, but the effective movement of the combination lever is decreased, as above explained. 45

Continued movement of the valve 26 rearwardly in the direction of the arrow shown on the 50 valve, takes place, but the movement from cut-off to release positions is retarded for the reasons above explained inasmuch as the distance between the pins 14 and 40 is still decreasing. The release position is shown on Figure 7, and is the 55 point at which the forward cylinder port 31 begins to be uncovered by the valve 26 for releasing the steam from in front of the piston. Subsequent to release, the event of compression occurs, at which time a small volume of steam is 60 trapped in advance of the piston to cushion it at the end of the stroke. It will be noted on Figure 8 that the rear cylinder port 31 is covered by the valve 26, and the piston 34 has approximately reached the end of its travel, steam remaining in the end of the cylinder being trapped and providing a cushion for the piston. The event of compression should take place late in the piston stroke and the above described mechanism enables such compression to take place 65 when merely sufficient steam is retained to cushion the piston when the latter has approached close to the end of the stroke. 70

Due to the mounting of the combination lever and its connection to the valve stem 25 through 75

the cross head and arms or links 38, the movement of the valve 26 from the point of release to that of compression is accelerated since the pins 14 and 40 are being moved apart due to the raising of the combination lever 16 by the upward swinging movement of the radius bars 20. Movement of the valve 26 is retarded in the intermediate portion of its travel or between the points of cut-off and release to make most 10 efficient use of the expansive properties of the steam, but at the opposite ends of the travel or at points of lead and compression, the movement of the valve is accelerated to admit an exhaust steam quickly to and from the cylinder 15 through the port openings and to provide merely sufficient compression to cushion the piston at the end of its stroke.

In order more clearly to point out the advantages of the above structure, attention is directed 20 to Figure 9 which is similar to Figure 5, like reference numerals being used with the addition of exponent *a*, except in Figure 9 there is shown a straight combination 16^a without the backset or rearward extension 36. The straight combination lever necessitates shortening of the link 38 and it will be seen from Figure 9 that the link 38^a is considerably shorter than the link 38. The angle between the link 38^a and the upper 25 end of the combination lever is approximately 57° whereas the similar angle shown in Figure 5 is approximately 25°. Since the parts in Figure 9 are in the same position as those in Figure 5, detail description of the operation is unnecessary, it being sufficient to point out that the lower end 30 of the combination lever is being moved by the union link 18^a to the left of the figure, the radius bars 21^a causing it to move downwardly while the upper end is moved forwardly by the valve rod 13^a. As hereinbefore pointed out, the combination lever 16 of Figure 5 moves upwardly 35 at this point instead of downwardly, because it is on the other side of the radius bars 21. Due to the sharp angle of the relatively short link 38^a, downward movement of the combination lever imposes such a cramping stress on the pin 40^a as to bind the valve stem crosshead in its 40 guide and if such downward and swinging movements continue the combination lever will either bend or break.

It would be impracticable to shorten the valve 50 stem 25^a and lengthen the link 38^a, because shortening the valve stem would reduce the clearance and prevent a valve stroke of proper length. Even if this could be done, the result 55 would be a decidedly different and noticeably inferior timing action.

Considering Figures 5 to 8 inclusive, and noticing the movement of the combination lever with respect to the pivot point 14, it will be noted 60 that it swings progressively to the left about that point from Figures 5 to 8. Since the point at which the link 38 is pivoted to the combination lever is to the left of the pivot point 14 in Figure 5, all of the pivotal movement about 14 tends 65 to raise that connection, swinging the link into line with the valve stem 25 and retarding the stroke of the valve until the position of Figure 7 is reached. In this position the portion of the combination lever about the link 38 is so nearly horizontal that its continuing movement about the pivot 14 is almost entirely a lifting movement, as has been pointed out. Obviously if the combination lever were straightened as indicated in Figure 9, the pivotal connection with 70 the link 38 would be to the right of the pivot 14

when starting from the position shown in Figure 5 and, therefore, this pivotal connection would be lowered by the swinging movement about the point 14 which would produce the opposite effect from that desired. Even in the position corresponding to those of Figures 7 and 8 there would be comparatively little lifting action, the final position of the pivotal connection between the link and combination lever being only about the same height as in Figure 5, so far as affected 10 by swinging about the point 14. Therefore, the desired effect upon the timing of the valve could not be obtained.

It is to be understood that numerous changes in details of construction, arrangement and operation may be effected without departing from the spirit of the invention, especially as defined in the appended claims.

What I claim is new and desire to secure by Letters Patent is:

1. Valve gear mechanism for steam engines having a driven rotatable member, a driven reciprocable member, a steam admission and exhaust valve, said mechanism comprising a vertically disposed combination lever deriving motion at its lower end portion from said reciprocable member and at its upper end portion from said rotatable member, a reciprocable cross-head for said valve, a depending radius bar pivoted to a lower portion of said combination lever, means providing a pivotal mounting for the upper end of said radius bar, a rearwardly extending portion on the upper end of said combination lever, and link means providing a connection between said crosshead and said rearwardly extending portion of said combination lever.

2. Valve gear mechanism for steam engines having a driven rotatable member, a driven reciprocable member, a steam admission and exhaust valve, said mechanism comprising a vertically disposed combination lever deriving motion at its lower end portion from said reciprocable member and at its upper end portion from said rotatable member, a reciprocable cross-head for said valve, a depending radius bar pivoted to a lower portion of said combination lever, means providing a pivotal mounting for the upper end of said radius bar, the upper end of said combination lever being bifurcated, a rearward extension on the bifurcated portion of said combination lever disposed close to the upper end thereof, and a yoke pivoted at one end to said crosshead and extending outwardly therefrom into pivotal engagement with and in straddling relation to said rearward extension.

3. Valve gear mechanism for steam engines having a driven rotatable member, a driven reciprocable member and a steam admission and exhaust valve, said mechanism comprising a vertically disposed combination lever deriving motion at its lower end portion from said reciprocable member and at its extreme upper end portion from said rotatable member, a reciprocable cross-head for said valve, a depending radius bar pivoted at its lower end to a lower portion of said combination lever, means providing a pivotal mounting for the upper end of said radius bar, and a link pivoted at one end to said crosshead, extending outwardly therefrom and pivoted at its opposite end to said combination lever a short distance below the upper end thereof.

4. Valve gear mechanism for steam engines having a driven rotatable member, a driven reciprocable member and a steam admission and exhaust valve, said mechanism comprising a com-

- bination lever deriving motion at its lower end portion from said reciprocable member and at its extreme upper end portion from said rotatable member, a reciprocable cross head for said valve,
5 a depending radius bar, a pivotal connection between a lower end portion of said combination

lever and said radius bar, a rearward extension on the upper end portion of said combination lever, and link means connecting said cross head and said rearward extension.

ALFRED O. JUDSON.
